UNITED STATES PATENT OFFICE.

ELZA L. ISAACS, OF WEST FRANKFORT, ILLINOIS, ASSIGNOR, BY MESNE ASSIGNMENTS,
TO AMERICAN BOILER WASHING DEVICE COMPANY, A CORPORATION OF ILLINOIS.

SEDIMENT REMOVER FOR BOILERS.

Application filed February 16, 1924. Serial No. 693,221.

My invention relates to improvements in sediment removers for boilers and has for its primary object a device in which sediment from boilers may be removed either by water or steam pressure.

A further object is to construct a sediment remover in which the gathering or accumulation of sediment around the blow-off valve while being removed, is prevented.

10 A still further object is to construct a sediment remover for boilers in which the sediment is removed by a series of jets, said jets commencing to act in sequence from the blow-off valve whereby the possibility of 15 clogging the blow-off valve by the accumulation of sediment is prevented.

My device is applicable to any type of steam boiler and for convenience sake will be shown and described as attached to a 20 locomotive or tractor boiler, as this type of boiler is more apt to have sediment accumulation than a stationary boiler where there are possibilities of at least a partial clarifying of the water used therein.

25 In the drawings:

Fig. 1 is a side elevation of a locomotive boiler with parts broken away and in section showing my device in position;

30 Fig. 2 is a vertical section taken on the line 2—2 of Fig. 1 looking toward the left;

Fig. 3 is a horizontal central section taken through the boiler and fire box with the tubes removed showing my device in position;

35 Fig. 4 is a perspective view of a portion of my device as removed from the boiler;

Fig. 5 is an enlarged longitudinal section of one of the nozzles employed;

40 Fig. 6 is an enlarged side elevation of the valve housing;

Fig. 7 is an end view of Fig. 6; and

Fig. 8 is an enlarged fragmental top plan view of the shield employed.

45 In the construction of my device I employ a boiler 9 which is equipped with fire tubes 10, a sediment ring 11, and a fire box 12. Adjacent the front of the boiler 9 is a diaphragm or head 13 which separates the water compartment 14 from the smoke box 15.

50 The boiler 9 is also provided with the usual steam dome 16. Secured to the steam dome 16 is a flange 17 in which a pipe 18 is secured. The pipe 18 is provided with an elbow 19 which also carries a pipe 20;

55 the free end of this pipe is secured in a

valve 21. The valve 21 is in turn connected to a pipe 22, the opposite end of which terminates in a check valve 23. Secured to the check valve 23 is a nipple 24 which carries an elbow 25. This elbow is in turn connected to a T 26, by means of a nipple 27. Carried by the T 26 is a pipe 28 which extends through the flange 29 carried by the boiler and which terminates in an L 30. Secured to the L 30 is a pipe 31; the pipe 31 passes through the head 13 and is provided with jam nuts 32, one of which is located on either side of the head 13 and said nuts are for the purpose of preventing any leakage between the water compartment 14 and 70 smoke box 15.

The pipe 31 extends rearwardly to a point over the sediment ring and has secured to its rearmost end an elbow 33. To this elbow is secured one end of a pipe 34, 75 the opposite end of which terminates in a T 35. Secured to the T are pipes 36 and 37 which carry elbows 38 and 39. Secured to the elbow 38 is a pipe 40 which carries an elbow 41, this elbow in turn carrying the 80 pipe 42, to the free end of which is secured an elbow 43 in which the pipe 44 is secured. The free end of the pipe 44 is bent outwardly, as indicated by the numeral 45, and this outwardly bent portion is pref- 85 erably reduced in diameter, the purpose of which will be explained in detail later.

The elbow 39 carries a pipe 46 which has an outwardly bent portion 47 similar in construction to the end 45. It will be noted 90 from Figs. 3 and 4 that the out-turned ends 45 and 47 of the pipes 44 and 46 terminate close together and extend outwardly and are in direct alinement with the opening in the sediment ring 11 which communicates 95 with the blow-off valve 48. The pipes 44 and 46 are provided with nozzles 49 which incline downward and project toward the valve 48. The elbows 38, 39, 41 and 43 are provided with nozzles 50 which are inclined 100 downwardly and project toward the corners of the sediment ring 11. While the pipes 36, 37, 40 and 42 are provided with nozzles 51 which incline downwardly and which extend in such a direction from the pipe 34 105 that the forces of water or steam passing therethrough will be directed in a continuous line around the sediment ring toward the blow-off valve 48. In other words, the nozzles carried by the pipes 36, 40, 42 and 110

44 will carry the water and sediment around substantially four sides of the sediment ring, while the nozzles carried by the pipes 37 and 46 will tend to drive the sediment and water around two sides. These streams of sediment and water however, meet directly at the blow-off valve and are forced there-through. It will be noted that the pipes 36, 37, 40, 42, 44 and 46 with the elbows connecting them, substantially form a loop disposed in the sediment ring.

Secured to the pipe 31 are nozzles 52; these nozzles extend downwardly and rearwardly and are located on alternate sides of the pipe 31. In this way a greater space is covered by the nozzles than would be if the same were placed directly underneath the pipe 31.

Located in the water chamber and at a distance above the pipe 31 is a shield 53. This shield is preferably concavo convex in form and is provided with a series of downwardly bent portions 54. These downwardly bent portions extend rearwardly, as illustrated in Fig. 1, and are for the purpose of preventing the sediment when stirred up from rising upward into the water chamber 14.

The shield 53 is provided with lugs 55 by means of which the same can be attached to the boiler shell so as to prevent its dislocation.

Secured to the T 26 is a nipple 56 which is secured in a check valve 57. This valve has secured thereto a pipe 58 which is in turn secured to a valve 59, the valve being attached to the branch pipe 60 of the injector pipe 61. The injector pipe is provided with a valve 62 by means of which the flow of water can be controlled there-through and a boiler check 63, the purpose of which is to prevent boiler pressure from entering the pipe 61.

Within each nozzle is secured a valve housing 64 which is provided with a stirrup housing 65 through which the valve stem 66 of the valve 67 extends. Secured over the end of the valve stem 66 is a nut 68 and surrounding the valve stem and between the nut 68 and stirrup 65 is a coil spring 69. The valve housing 64 is of course provided with a seat, against which the valve 67 can be seated, and the purpose of the nut and spring is to regulate the valve. In other words, adjust the valve 67 so that its opening can be made more or less sensitive. The purpose of this will be explained in detail.

The operation of my device is as follows—

After the same has been installed within a boiler and the boiler operated for a certain length of time, a certain amount of sediment will lodge in the sediment ring and in the water chamber. When it is desired to remove this sediment by means of steam pressure, the valve 21 is opened which permits steam to pass from the steam dome

through the pipe 22, check valve 23 and the various other pipe connections into the pipe 31. It is understood of course, that the blow-off valve 48 has been opened just prior to the opening of the valve 21. The steam thus admitted will first pass out through the reduced ends 45 and 47, and in passing through the valve 48 speed up the passage of water. The openings in the reduced ends 45 and 47 however are not sufficient to permit the steam to escape therefrom as rapidly as it passed through the pipes and in this way the adjustability of the valves 67 is brought into action. These valves are set in the following manner—As soon as a slight degree of excess pressure is created in the pipes 44 and 46, caused by the choking of the steam on account of the reduced ends 45 and 47, the nozzles 49 commence to act, that is, the valves located therein open up, and the jets issuing therefrom impinging on the bottom of the sediment ring carry the sediment to the blow-off valve where it is carried away.

After these valves have been opened the valves in the nozzles on the cleaning piping will yield successively beginning with the nozzles adjacent to the valve 48, the nozzle valves being loaded to yield progressively, the last valve to open being the one carried by the nozzle adjacent the diaphragm or head 13, it being understood, of course, that when the last mentioned nozzle is opened, all of the nozzles are in operation. In this way I accomplish a gradual or step by step cleaning of the sediment, commencing at the blow-off valve and gradually advancing to the end of the boiler. This action prevents the possibility of a great amount of sediment being suddenly carried to the blow-off valve and clogging the same, which would be the possibility were all the nozzles opened simultaneously, or were the nozzle adjacent the head 13 opened first.

The shield 53 has a tendency to prevent any sediment stirred up by the nozzles in the boiler from being churned or raised upward therein, due to the fact that the downwardly bent portions have a tendency to direct the movement of these particles of sediment toward the bottom of the boiler, the steam passing through the water naturally creates a current therein and this current is also deflected toward the bottom of the boiler and in being so deflected causes the shield to have what may be termed a Venturi action. That is, to draw fresh water down through the openings in the shield. This action will not only have a tendency to increase the speed of the water but will also tend to remove any sediment from the top of the shield.

If it is desired to use water instead of steam or in other words use the injector, the valves 21 and 62 are closed, the valve 59 opened and the injector, not shown, placed in

action. In this instance, water pressure instead of steam is used through the cleansing system, but the resulting action will be exactly the same.

5. My device may be used either in fire tube or water tube boilers and is intended to remove sediment and is not for the purpose of removing a hard baked scale. It can however, be used to advantage with boiler compounds which soften and loosen the scale and precipitate it in the boiler in the form of sediment.

It is to be further noted that the valves in the nozzles seat inwardly so that there will be no danger of the boiler pressure unseating the valves and causing sediment to gather on the valve seats.

While only steam and water have been mentioned in this specification, it is obvious 20 that any fluid, either gaseous or liquid, under pressure may be used in connection with my device without departing from the spirit of my invention.

It is also to be understood that during the washing of the boiler sufficient water is constantly supplied therein to replace the water passing out through the blow-off valve and thus the consequent reduction of boiler pressure due to the water passing through this 30 valve is eliminated.

Having fully described my invention, what I claim is:—

1. A sediment remover for boilers comprising a pipe, a plurality of nozzles carried by said pipe, valves located in said nozzles and loaded to be opened successively by fluid pressure and means for admitting a fluid under pressure to said pipe and nozzles.

2. A sediment remover for boilers comprising a pipe, a plurality of nozzles carried by said pipe, self-closing valves located in said nozzles and adapted to be opened by the fluid supplied to said nozzles, means for admitting a fluid under pressure to said pipe and nozzles, and means for regulating said valves so as to permit sequential opening thereof by the pressure in said pipe.

3. A sediment remover for boilers comprising a plurality of pipes, a plurality of nozzles carried by said pipes, valves carried by said nozzles, means for regulating said valves for sequential automatic opening when pressure is applied thereto, and means for imparting pressure to said valves through said pipes and nozzles, whereby said valves are held open.

4. The combination with a boiler shell having a blow off valve thereon of a sediment remover mounted in said shell, said remover comprising a plurality of connected pipes, nozzles carried by said pipes and arranged at different distances from the blow off valve and directed to move the sediment toward the same, valves disposed one in each pipe and loaded to open sequentially from

the blow off valve and means for supplying a cleaning fluid under pressure to the sediment remover.

5. The combination with a boiler provided with a blow off valve, of a sediment remover, 70 said remover comprising a plurality of pipes extending around the sediment ring of a boiler and terminating adjacent the blow-off valve thereof, a pipe connected to said pipes and extending within main portion of said 75 boiler, nozzles carried by all of said pipes and the nozzles on the last-mentioned pipe extending parallel thereto, said nozzles so arranged as to create a continuous current to the sediment ring and around the interior 80 thereof to the blow-off valve, valves located in said nozzles and arranged for sequential opening commencing adjacent the blow-off valve, and means for admitting a fluid under pressure to said pipes whereby said valves 85 are all sequentially and automatically opened and so maintained whereby a continuous movement toward the blow-off valve is imparted to sediment in the sediment ring and said main portion while the blow-off valve 90 remains open.

6. The sediment remover of claim 5 in which the valves are provided with means for adjusting them so that a pressure progressively increasing from a predetermined 95 minimum will be required to unseat the same.

7. The combination with a boiler of a sediment remover and means for connecting the remover to a source of fluid under pressure; said boiler comprising a barrel, a sediment ring and a blow-off valve positioned to control the discharge from said ring, and said remover comprising a pipe disposed along the bottom of said barrel, a second 105 pipe looped around said ring and having open ends adjacent said blow-off valve, means connecting said pipes and nozzles mounted upon said pipes and arranged to discharge fluid from said source against 110 the sediment in said boiler, the nozzles on the first pipe arranged to discharge fluid to sweep the sediment towards the sediment ring and the nozzles on the second pipe arranged to discharge fluid to force the sediment in directions to reach the blow-off 115 valve, each of said nozzles being provided with means to spread the stream of fluid being discharged therefrom.

8. The combination with a boiler of a 120 sediment remover and means for connecting the remover to a source of fluid under pressure; said boiler comprising a barrel, a sediment ring and a blow-off valve positioned to control the discharge from said ring, and said remover comprising a pipe disposed along the bottom of said barrel, a second 125 pipe looped around said ring and having open ends adjacent said blow-off valve, means connecting said pipes and nozzles 130

mounted upon said pipes and arranged to discharge fluid from said source against the sediment in said boiler, the nozzles on the first pipe arranged to discharge fluid to sweep the sediment towards the sediment ring and certain of the nozzles on the second pipe being arranged to discharge fluid merely to stir up the adjacent sediment in the corners and the rest of said nozzles to stir up the sediment adjacent thereto and cooperate in forcing the stream of sediment in directions to reach the blow-off valve.

9. A cleaner comprising a pipe, a plurality of other pipes arranged to form a loop, means connecting the first-mentioned pipe to said loop, and a plurality of nozzles

mounted on each pipe, the nozzles on the first-mentioned pipe disposed on opposite sides thereof and arranged to discharge forwardly thereof and parallel thereto, and the nozzles on said loop arranged to discharge outwardly of said loop, certain of said nozzles disposed to discharge forwardly with respect to the pipe carrying the same, and the rest of said nozzles arranged to discharge laterally with reference to the respective pipes, and said connecting means being disposed at an angle to the first-mentioned pipe and to the plane of the loop.

In testimony whereof, I have signed my name to this specification.

ELZA L. ISAACS.
